COMBINED SUSPENSION FILE SUPPORT AND INDEX TAB

Frank D. Jonas, East Williston, N. Y., assignor to Oxford Filing Supply Co., Brooklyn, N. Y., a partnership comprising Richard A. Jonas, Richard A. Jonas, Jr., Robert P. Jonas, Frank D. Jonas and Edward F. Jonas

Application October 8, 1941, Serial No. 414,065

7 Claims. (Cl. 129—16.7)

This invention relates to filing folders of the suspension type and is particularly concerned with a structure by means of which the folders are supported, including adaptation of such means so as to make it a component part of an index or data tab.

The general object of this invention is the provision of a structure of this type in a simple, inexpensive form adapted to be rapidly manufactured on a production basis.

Other and more detailed objects of the invention will be at once appreciated in connection with the following detailed description of several embodiments thereof.

This invention resides substantially in the combination, construction, arrangement and relative location of parts as will be described in detail below.

In the accompanying drawing,

Figure 1 is an end edge elevational view of a filing folder in accordance with this invention;

Figure 2 is a front elevational view thereof with the transparent casing omitted;

Figure 3 is a front elevational view of a modified form of construction with the transparent casing omitted;

Figure 4 is an end edge elevational view thereof with the casing in place; and

Figure 5 is a perspective view of the combined suspension rod and index tab of this invention.

This invention is concerned with improvements in suspension files generally, of which several forms are illustrated in full detail in my copending application Serial No. 303,729, filed November 10, 1939, entitled "Filing folder."

As illustrated in Figure 1, suspension filing folders of this general type are formed from a single sheet of suitable material by folding along a medial line to form a V-shaped pocket. Such a folder is illustrated at 10 in Figure 1 and formed by folding the sheet along the medial line 11. The folder is suspended from its two free edges by means of bars or rods attached adjacent these edges in any one of a number of different ways, which bars or rods terminate in hooked ends which may be rested upon suitable supports so as to suspend the file and its contents therefrom.

The front flap of the folder, as indicated in Figures 1 and 2, is supported by means of rod 14 which lies in a tubular socket formed by folding the terminal edge of the front flap inwardly upon itself along the line 12 and gluing the free edge down against the front body portion along the area 13. Thus the front suspension rod 14 may be removably mounted in the flat tubular

space thus formed by sliding it endwise thereinto. As illustrated in my above mentioned application, the ends of the rod 14 may be offset in opposite directions to hold the rod longitudinally in place.

5 In the usual practice the rear flap of the suspension file is supported in a similar way by means of another rod.

However, in accordance with this invention the rear suspension rod is modified so that it may 10 perform in addition to its supporting function the function of forming an index tab. As shown, the rod consists of a portion 15 terminating in hooked ends offset as before and attached to the inside face of the rear flap of the file in any suitable manner as indicated at 16. The attachment, as 15 illustrated at 16, consists in striking out of the portion 15 of the rod at a plurality of points to form a series of fingers 16' which pass through the rear flap and are bent over to secure the rod to the flap. Of course, the rod may be attached in other ways, as illustrated for example in Figures 3 and 4 to be described later.

As clearly illustrated in Figure 5, the rod has 20 integral with the portion 15 an upwardly extending portion 17 which is bent along a medial line A rearwardly of the plane of the portion 15, as is clearly seen from the figures. A series of ears 18 are struck out from the portion 15 and are bent so as to lie in the plane of the portion 17 to form extensions thereof. A transparent 25 casing of suitable material as indicated at 19 is shaped so that it may be slidably mounted on the rod by reason of the enveloping of the upper edge of the portion 17 and the aligned lower edges of the tabs 18 by the inturned edges of the casing 19. In use a paper strip, not shown, is mounted within the casing so that marks made thereon 30 will be exposed therethrough. With this arrangement it will be seen that the rear rod of the suspension rod performs a function of suspending the file and forming an indicator tab extending 35 all the way across the width of the folder.

In the modification shown in Figures 3 and 4 40 the folder is of the same construction as previously described with respect to the front flap, but in this case the rear flap is inturned upon itself along the line 20 and glued down to the inner face of the rear flap along the area 21 to form a somewhat larger flap channel similar to the channel on the front flap. Before this flap 45 is folded in and glued in place a series of holes 23 are cut therein so as to be exposed on the inner face of the rear flap, as indicated in Figure 3. A rod like that shown in Figure 5 is inserted 50 in the flap channel thus formed, so that the ears

18 will project through the holes 23. The channel in this case is sufficiently large to permit of enough space to insert the rear rod notwithstanding the projecting ears 18 which by twisting the rod may be caused to project through the holes 23.

In this case it will be seen that the upwardly and rearwardly extending flange 17 is encased within the walls forming the channel, as clearly indicated in Figure 4. As before a transparent casing 19 may be slid in place to enclose an indicator strip. The difference in this case is that the upper reversely curved edge of the casing 19 not only surrounds the upper edge of the flange 17 but also the enclosing portions of the rear wall 15 of the folder. The lower reversely curved edge 15 of the casing 19 encircles the ends of the ears 18 as before.

From the above description it will be apparent to those skilled in the art that the device of this invention may be embodied and assembled in other physical forms, and I do not, therefore, desire to be limited by the illustrated disclosure, but rather by the true scope of the claims granted me.

What is claimed is:

1. In a device of the type described the combination comprising a V-shaped filing folder having a pair of suspension bars at its free edges for suspending the folder thereby, one of said bars having a plain portion extending rearwardly thereof and a struck out portion lying in the same plane with the plain portion, and a transparent casing engaging the free edge of the plain portion and the edge of the struck out portion.

2. In a device of the type described the combination comprising a V-shaped filing folder having a pair of suspension bars at its free edges for suspending the folder thereby, one of said bars having a plain portion extending rearwardly thereof and a struck out portion lying in the same plane with the plain portion, and a transparent casing slidably engaging the free edge of the plain portion and the edge of the struck out portion.

3. In a structure of the type described the combination comprising a pocket folder, including front and back walls, the terminal edges of said

walls being folded upon themselves to form channels, one of the inner channel walls having a plurality of apertures, suspension bars mounted in said channels, one of said bars having a longitudinal portion inclined rearwardly of the remainder, and ears struck out of said other portion so as to project through said apertures and lying in the plane of said inclined portion.

4. In a structure of the type described the combination comprising a pocket folder, including front and back walls, the terminal edges of said walls being folded upon themselves to form channels, suspension bars mounted in said channels, one of said bars having a longitudinal portion inclined rearwardly of the remainder, and ears struck out of said other portion and lying in the plane of said inclined portion, and a transparent casing slidably mounted on said inclined portion and said ears.

5. A supporting bar for a suspension filing folder consisting of an elongated strip of suitable material terminating in hooked ends, a portion of said strip being bent along a medial line into an angular plane with respect to the other portion, and a part of said other portion being struck out so as to lie in the plane of said angular portion.

6. A supporting bar for a suspension filing folder consisting of an elongated strip of suitable material terminating in hooked ends, a portion of said strip being bent along a medial line into an angular plane with respect to the other portion, and a part of said other portion being struck out in the form of a plurality of spaced ears so as to lie in the plane of the angular portion.

7. In a structure of the type described, the combination comprising a pocket folder, including front and back walls, the terminal edges of said walls being folded upon themselves to form channels, one of the inner channel walls having a plurality of apertures, suspension bars mounted in said channels, one of said bars having a longitudinal portion inclined rearwardly of the remainder, and ears struck out of said other portion so as to project through said apertures, and a transparent casing slidably mounted on said inclined portion and said ears.

FRANK D. JONAS.
